UNITED STATES PATENT OFFICE.

MARTIN T. KERCHER AND NOBLE N. TOMBAUGH, OF ROANN, INDIANA.

RAIL-JOINT.

1,165,264.

Specification of Letters Patent. Patented Dec. 21, 1915.

Application filed May 22, 1915. Serial No. 29,855.

To all whom it may concern:

Be it known that we, MARTIN T. KERCHER and NOBLE N. TOMBAUGH, citizens of the United States, residing at Roann, in the 5 county of Miami and State of Indiana, have invented new and useful Improvements in Rail-Joints, of which the following is a specification.

The present invention relates to improvements in means for connecting the meeting ends of two railway rails, and the primary object of the invention is to provide a joint for rail ends wherein the employment of bolts and nuts therefor will be entirely dispensed with.

With the above and other objects in view, the improvement resides in the construction, combination and arrangement of parts set forth in the following specification and 20 falling within the scope of the appended claims.

In the drawings: Figure 1 is an elevation of two rails connected in accordance with the present invention, Fig. 2 is a transverse 25 sectional view approximately on the line 2—2 of Fig. 1, Fig. 3 is a horizontal sectional view approximately on the line 3—3 of Fig. 1, and Fig. 4 is a detail sectional view approximately on the line 4—4 of 30 Fig. 1.

Referring now to the drawings in detail, 1—1 designate two alining rails of the ordinary construction. In the present instance, however, we channel the underfaces of the 35 heads of the rails longitudinally for a suitable distance from their ends, the said channels being indicated by the numerals 3. The base flanges of the rails, at suitable points adjacent the ends thereof have their longitudinal edges notched, as indicated by the 40 numeral 4.

The numeral 5 designates a rail chair, the same including a base 6 upon which the rails rest, vertical extensions projecting from the 45 opposite longitudinal edges of the base, indicated by the numeral 7, inwardly inclined flanges 8 overlying the base flanges of the rails and vertically extending integral plates 9 which contact with the webs of the rails. 50 The plates 9 upon their upper edges have their inner corners formed with longitudi-

nally extending beads 10 which are adapted to be received within the channels 3 in the underfaces of the heads of the rails, it being understood that the rails are arranged 55 upon the chair by sliding the same toward each other from the opposite ends of said chair. The vertical edges as well as the inclined flanges of the chair, at suitable points adjacent its ends, are formed with 60 notches 12 which are adapted to register with the notches in one of the longitudinal edges of the base flange of the rails, and secured within the said notches 12, at the lower wall thereof, or the wall provided by 65 the base of the chair are bendable clips 14, the said clips being of a sufficient length to be bent over the angular flange of the chair when the same are brought into engaging 70 position with the notches in the rail and if 7 desired the bent portions, indicated by the numerals 15, may be formed with openings 75 for the reception of holding elements 16 which pass therethrough and enter suitable openings in the inclined flanges of the chair, this latter construction being illustrated in detail in Fig. 4.

From the above description, taken in connection with the accompanying drawings, the simplicity of the device, as well as the 80 advantages thereof will, it is thought be perfectly apparent to those skilled in the art to which such invention appertains without further detailed description.

Having thus described the invention, what 85 we claim is:

1. In combination, two alining rails, a chair upon which the rails rest, said chair having its longitudinal edges notched and the base flanges of the rails having notches 90 which register with the notches in said chair, of malleable fingers arranged within the notches in the chair and adapted to be bent into engagement with the notches in the rails.

2. In a rail joint, two alining rails having the underfaces of their heads channeled longitudinally, a chair upon which the rails rest, and which includes vertical plates that are disposed to the opposite sides of the 100 webs of the rails and having their upper edges formed with longitudinal beads which

are received in the channels of the rails, the edges of the chair and the edges of the rails having registering notches, malleable fingers secured within the notches of the chair and adapted to be bent into engagement with the notches in the rails, and means for locking the bent edges of the malleable members upon the chair over the rails.

In testimony whereof we affix our signatures in presence of two witnesses.

MARTIN T. KERCHER.
NOBLE N. TOMBAUGH.

Witnesses:

ALBERT WARD,
JAMES J. WILSON.
